ANCHORING DEVICE

John Chmura, Marmarth, N. Dak.

Application May 29, 1939, Serial No. 276,424

1 Claim. (Cl. 238—379)

My invention relates to anchoring devices and more particularly to anchoring devices for securing foot guard-blocks to rails and the like.

It is a common practice to secure foot guard-blocks to rails, frogs, switch and guard rails to preclude persons from accidentally catching their feet beneath the head of the rails thereby eliminating serious injury and often resultant loss of life. The foot guard-blocks are usually secured between the heads and flanges of the rails by means of anchoring or securing devices, an example of devices of this character being illustrated in the United States Letters Patent, Nos. 698,314 and 1,743,419.

Due to vibratory movement imparted to the rails, by the rolling stock passing thereover, various parts, for instance the blocks, anchoring devices and/or rails, become worn to such a degree as to eliminate the effectiveness of the anchoring devices, thus permitting the blocks to creep or become displaced from desired positions relative to the rails.

My invention overcomes the foregoing disadvantages and undesirable results, it being one of the principal objects thereof to provide an anchoring device for association with a rail and guard-block which is so constructed and arranged as to effectively anchor the guard-block to the rail in a manner to preclude creeping or dislodgement thereof relative to the rail.

An important object of my invention is to provide an anchoring device of the above described character so constructed and arranged whereby, upon vibration, the effectiveness of the device will be maintained, thus securely clamping the guard-block to the rail against movement relative thereto.

A significant object of my invention is to provide a device of the above described character so constructed as to be applicable to rails and blocks of various sizes, thereby maximizing the utility thereof.

Another object of my invention is to provide an anchoring device of the above described character fashioned with means coacting with both the rail and guard-block for firmly and reliably clamping or anchoring the guard-block to the rail.

A further object of my invention is to provide an anchoring device equipped with resiliently actuated means for maintaining said device in cooperative relation with said rail and guard-block whereby to secure said guard-block fixed to said rail against accidental displacement.

A still further object of my invention is to pro-

vide a device of the above described character which is simple in construction, durable in use, efficient in operation and economical in manufacture.

A special object of my invention is to provide a device of the above described character which is easily applied to and readily detached from a rail and guard-block organization.

Other objects and advantages will be apparent from the following description, appended claim and annexed drawing.

Referring to the drawing wherein like reference characters designate like parts throughout the several views:

Figure 1 is a perspective view of an anchoring device constructed in accordance with my invention.

Figure 2 is a side elevation thereof illustrating the device as applied to a rail and guard-block organization, the latter being illustrated in transverse section.

Figures 3 and 4 are diagrammatic views illustrating the anchoring device as applied to rails of different sizes.

In reducing my invention to practice, I provide a rail and block organization 5 comprising a rail 6 of ordinary construction provided with the usual head 7 formed on the upper end of a web 8, the lower end of the latter being integrally connected to a flange or base 9 intermediate the marginal edges or sides 10 thereof. The organization 5 also comprises a foot guard-block 11 having an inner face juxtapositioning a side face of the web 8 and upper and lower faces engaging the lower and upper faces of the head and flange respectively.

The block 11 is formed with an inclined lateral outer face 12 which extends between a lower outer corner of the head and an upper outer corner of the flange as illustrated in Figure 2. The foregoing is descriptive of a rail and block organization of ordinary construction and it is to be understood that the organization per se forms no part of the present invention except as in combination with my novel form of anchoring device 13 as hereinafter set forth.

My anchoring device 13 comprises an elongated member having a base section 14 appressingly underlying the under face of the flange 9 and terminating at one end in an integrally formed and upwardly extending arm or side section 15, the upper end of which is angularly and inwardly disposed to constitute a penetrant element 16, the latter being of an odontoid or cuneiform configuration for penetrating the face 12.

of the block 11 between the upper and lower ends thereof as illustrated in Figure 2 of the drawing. The opposite end of the section 14 is fashioned with an upwardly extending portion 17 or hook element 17, the latter engaging the adjacent side 10 of the flange 9 and appreciably overlying a portion of the upper face of said flange.

The lower end of the arm or side section 15, adjacent the jointure thereof with said base section 14, is of an arcuate configuration and extends a material distance away from the adjacent side 10 of the flange 9 whereby to space said section 15 relative to the face 12 of the block 11. The member or section 15 thereof is of a resilient construction to coact with the portion 17 and element 16 for urging the latter into penetrating engagement with the block 11, it being understood that when the device is applied to the organization the section 15 is normally tensioned outwardly by the block 11, thus vibration imparted to the organization by rolling stock passing over the rail tends to urge the element 16 deeper into the block and thereby maintains the block effectively clamped or anchored to the rail.

It will be noted, by reference to Figure 2 of the drawing, that when the device is in assembled condition with respect to the organization an appreciable space is provided between the block and section 15 whereby a tool may be inserted therebetween for disconnecting the element 16 from the block and thus enabling the device to be detached from the organization. When it is desired to assemble the device, the portion 17 is disposed over an edge 10 of the flange 9 and the section 14 expanded outwardly and moved upwardly to effect appressed engagement of the section 14 with the under face of the flange 9, whereupon said section 15 is released for permitting penetrating engagement of the block 11 by the element 16.

As diagrammatically illustrated in Figures 3 and 4 of the drawing, the resiliency of the member 14 or arm 15 permits of the device being utilized in connection with rails of various sizes. The rail depicted in Figure 3 is of a larger size, for instance 100 lbs., than the rail depicted in Figure 4, the latter, for instance, being of the 85 lb. type. Thus it will be understood that my device lends itself to a greater utility than that

type of an anchoring device for use in connection with a rail of one standard size.

This novel adaptation of my anchoring device to rails of various sizes is obtained by constructing the section 14 of a relatively long length and thereby spacing the lower end of the section 15 an appreciable distance away from the adjacent edge 10 of the flange 9 and which results in stress being applied to the block and rail by the coaction of the portion 17 and element 16, the center line of stress being disposed in a plane angularly related to the under face of the flange and intersecting the jointures of the portion 17 and element 16 with the rail and block respectively and which line is indicated by the dot and dash line A—A on Figure 2 of the drawing.

From the foregoing it will be apparent that my invention provides a simple and effective means for anchoring foot guard-blocks to rails and the like. It is obvious that the invention is not confined to the herein described use therefor as it may be utilized for any purpose to which it is adaptable. It is therefore to be distinctly understood that the invention is not limited to the specific construction as illustrated and described, as the same is only illustrative of the principles of operations, which are capable of extended application in advance forms, and that the invention comprehends all construction within the scope of the appended claim.

Having described my invention I claim:

A device of the character described, comprising, an elongated resilient member having a base section adapted to underlie the flange of a rail and terminating at one end in an upwardly extending side section fashioned on the upper end thereof with a cuneiform element adapted to penetrate a foot guard-block disposed adjacent the web and between the head and flange of said rail, said base section terminating at the opposite end in a hook element adapted to embrace the adjacent edge of said flange and appreciably overlie a portion of the upper face of said flange, said side section having a lower end of an arcuate configuration adapted to space said side section away from said block and to normally urge said element into said block when said side section is tensioned by said block whereby to anchor said block to said rail.

JOHN CHMURA. 50
